PLAYGROUND CLIMBING DEVICE

Richard F. Kishel, 508 N. McKinley Ave., Muncie, Ind.

Filed Jan. 27, 1961, Ser. No. 63,732

Term of patent 14 years

(Cl. D34—5)

FIG. 1

FIG. 2

FIG. 1 is a front elevational view of a playground climbing device showing my new design. FIG. 2 is a top plan view thereof.

The dominant features of my design reside in the portions shown in full lines.

I claim:

The ornamental design for a playground climbing device, as shown and described.
